UNITED STATES PATENT OFFICE.

EDWANA E. WRIGHT, OF ATLANTA, GEORGIA.

DUST-COLLECTOR FOR RADIATORS.

1,246,212.

Specification of Letters Patent. Patented Nov. 13, 1917.

Application filed February 1, 1915, Serial No. 5,598. Renewed May 12, 1917. Serial No. 168,817.

To all whom it may concern:

Be it known that I, EDWANA E. WRIGHT, a citizen of the United States, residing at Atlanta, in the county of Fulton and State 5 of Georgia, have invented certain new and useful Improvements in Dust-Collectors for Radiators, of which the following is a specification.

My invention relates to dust collectors 10 for radiators and has for its primary object to provide a simple and inexpensive device which may be applied to radiators to prevent the dust from circulating past the radiator and soiling the walls and ceiling.

Another object of my invention is to construct the device in such a manner that the dust shield may be constructed of paper, thereby being readily removed when it has 15 become worn or unsightly, and a new shield placed in its stead.

Another object of my invention is to construct the shield supporting and attaching frame of the device in such a manner as will permit it to be used on any size radiator.

Still another object is to so construct the device that the parts may be packed for shipment in a very small and neat package.

With these objects in view, the invention will be more fully set forth by referring to 20 the illustrative embodiment shown on the accompanying drawings.

In said drawing:

Figure 1 is a side view of a radiator with the invention applied thereto.

Fig. 2 is a vertical section on the line 2-2 of Fig. 1, showing the bracket constructed for use on a radiator which may be set away from the wall.

Fig. 3 is an end view of a modified form 40 of bracket.

Fig. 4 is a side view of the device with the parts assembled.

Fig. 5 is a perspective view of the preferred form of bracket showing the shield 45 supporting and attaching rods in position.

Fig. 6 is a sectional view of a radiator with the invention applied thereto showing the bracket constructed for use on a radiator which may be set close to the wall.

Fig. 7 is a modified form of the invention.

Fig. 8 is a perspective view of a part of the modified form of shield supporting and attaching rods.

Referring to the drawings in detail, A

represents a radiator of a conventional type and 1 represents a vertical bracket constructed for attachment on the section connector B of the radiator by means of U-shaped clamps 1^a, as shown in Figs. 1, 2, 4, 5 and 7, or by means of clamps 1^b, as shown in Fig. 3. In the former construction of the clamps a bolt 1^c is used to securely hold the clamp in position, but in the latter construction the clamp is constructed of spring steel and the ends are so disposed as will permit the clamp to engage the section connector B and be held in place by friction. 2 represents the parallelly disposed shield supporting and attaching rods. These rods are constructed with two telescoping sections in order that they may be used on radiators of different lengths. 3 represents counter-sunk grooves provided on the brackets 1 in which the rods 2 are seated. 4 represents the dust shield having an extension apron 4^a, which may be made of any suitable material, but preferably paper, and in the present case it has been found by using a paper having a roughened surface, the dust is more readily collected and caused to adhere to the surface of the shield. The shield may be attached to the frame in any desired manner; the manner illustrated is probably the preferred manner, to wit, by passing the cotter pins 5 through the shield and one of the openings 6 in its supporting rods 2, then through the opening in the counter-sunk groove on the bracket. This manner of attaching the shield will simplify changing an old shield when desired. By providing a plurality of the openings 6, the frame is more readily adjustable to radiators of different lengths; however, in most instances, the desired adjustment of the length of the frame may be realized by the telescoping members 2, and thereby make it unnecessary to provide more than one opening as shown in the modification in Fig. 7. While I have not pointed out specifically the particular design of the bracket members, it is to be understood that they may be constructed with their diverging sides of any pitch in order that they may accommodate radiators either positioned close or some distance from the walls.

I claim:

1. A dust collector for radiators comprising a frame, a shield supported thereon, 110

2

said frame comprising vertical bracket members having U-shaped attaching clamps for attachment to the section connector of the radiator, a bolt engaging said U-shaped 5 clamps for clamping it on said section connector, a plurality of shield supporting rods carried by the bracket members, and means for attaching said shield and its supporting rods to said bracket members.

10 2. A dust collector for radiators comprising a take down frame, a removable paper shield supported thereon, said frame comprising vertical bracket members adapted to extend above the radiator, U-shaped 15 clamps on said bracket for attachment to the section connector of the radiator, bolts connecting said clamps and passing under the section connector, said vertical bracket members being provided with counter-sunk 20 grooves, a plurality of shield supporting rods carried by the bracket members in said counter sunk grooves, and cotter pins

passing through the shield and its supporting rods and said bracket member.

3. A dust collector for radiators comprising a take down frame constructed for attachment to the radiator and adapted to extend above the same, a removable paper shield supported on said frame to trap the dust circulating through the radiator, 25 said take down frame comprising vertical bracket members having clamps for attachment to the section connector of the radiator, and a plurality of telescoping shield 30 supporting and attaching rods supported 35 on said bracket members, and cotter pins for connecting the shield to said frame.

The foregoing specification signed at Atlanta, Ga., this 29th day of January, 1915.

EDWANA E. WRIGHT.
